FLOOR PANEL

Frederick N. Rushton, Baltimore, Md., assignor to Washington Aluminum Company, Inc., Baltimore, Md., a corporation of Maryland

Filed Jan. 18, 1961, Ser. No. 63,610

Term of patent 14 years

(Cl. D13—1)

FIG. 1.

FIG. 2.

FIG. 3.

FIG. 1 is a top plan view of a floor panel, showing my new design, the center thereof being broken away to indicate indeterminate length;

FIG. 2 is a bottom plan view thereof; and

FIG. 3 is an enlarged cross-section taken in the direction of the arrows and along the line 3—3 of FIG. 1.

I claim:

The ornamental design of a floor panel, as shown and described.
